UNITED STATES PATENT OFFICE.

JAMES H. SPENCE, OF MILWAUKEE, WISCONSIN.

WATER-BACK.

SPECIFICATION forming part of Letters Patent No. 402,994, dated May 7, 1889.

Application filed November 7, 1888. Serial No. 290,195. (No model.)

To all whom it may concern:

Be it known that I, JAMES H. SPENCE, of Milwaukee, in the county of Milwaukee and State of Wisconsin, have invented new and 5 useful Improvements in Water-Backs; and I do hereby declare the following to be a full, clear, and exact description of said invention, reference being had to the accompanying drawings, and to the letters or figures of reference marked thereon, which form a part of 10 this specification.

My invention relates to that class of devices which is used for heating water in connection with water-service pipes, the device being located in or alongside the fire-box of a kitchen 15 coal or wood burning stove.

The novel features of my invention will be hereinafter distinctly claimed.

In the drawings, Figure 1 is a perspective 20 view of my newly-invented water-back, a central portion being broken away for convenience of illustration. Fig. 2 is a vertical section of the same device on line X X of Fig. 1. Fig. 3 is a vertical transverse section of the 25 same device on line Y Y of Fig. 1, showing also the top and front of the stove in section in connection with a portion of the grate at the bottom of the fire-box. Fig. 4 is an inner side elevation of the left-hand water-back end 30 head seen in Fig. 1. Fig. 5 is an end view of the rear wall of the water-back, showing its construction with reference to connecting it with the end head seen in Fig. 4. Fig. 6 is a vertical central longitudinal section of a modified form of water-back. The arrows in Figs. 2 and 6 show the direction of the flow of water in the pipes. The arrows in Fig. 3 indicate the direction of the inflow of air or draft to the fire-box.

40 The heads A and A' of the water-back are constructed of cast-iron, and are provided with chambers B and B'. An inlet or induction pipe, C, passes through the head A', and turns by a screw-thread into an aperture therefor 45 in the head A, which aperture opens into the chamber B, whereby the inlet-pipe C is adapted to convey water into the chamber B. Two more pipes, D and E, (in the form shown in Figs. 1 and 2,) are inserted at one end into 50 apertures therefor in the head A, opening into the chamber B, and at the other end are inserted in the head A' in apertures therefor

opening into the chamber B', and an outlet-pipe, F, is inserted in an aperture therefor in the outside of the head A', opening into the 55 chamber B' and leading therefrom, which serves as an outlet or ejection pipe for the water. By this method of construction there is a free circulation of the water through the pipes C, D, and E and through the chambers 60 B and B'. These pipes are wrought-iron gas-pipes, and the pipes D and E are provided at their ends with right-hand and left-hand screw-threads, respectively, whereby they are adapted to turn into corresponding screw- 65 threads in the heads A and A'.

In the modified form shown in Fig. 6 a fourth pipe, F', is used as an outlet-pipe, and this pipe is, for convenience, made to pass through the head A' and turn into the head 70 A, entering one of the chambers B. (Shown in the modified form in Fig. 6.) This form of device is intended and adapted to be placed longitudinally in the fire-box of a kitchen-stove opposite to and alongside of the front 75 of the stove, the head-pieces A and A' being located at the respective ends of the fire-box, and being held in position by the pipes, and also by the rear wall, G, which is constructed of cast-iron, and is secured at its respective 80 ends to the heads A and A', preferably by means of lugs II, projecting therefrom, which enter sockets K K, provided therefor in the respective heads A and A'. This wall G also serves to protect the front of the stove from 85 the excessive heat of the fire in the box, and is preferably provided at its lower edge with a series of apertures, H H, through which air is permitted to pass from the outside into the fire-box, as indicated in Fig. 3, the top of the 90 stove being indicated at L, the side at M, and the grate forming the bottom of the fire-box at N in Fig. 3. The heads A and A' are also preferably provided with flanges O and O' for receiving thereon and forming a connection with the necessary fire-bricks for lining the ends of the fire-box.

It will be understood that this form of water-back is very cheaply and readily constructed, in that the heads A and A' and the 100 wall G are readily molded and cast of iron, and that the pipes are made of the ordinary and cheaply-constructed wrought-iron gas-pipe. This water-back is also admirably

- adapted for the use for which it is intended, in that the head-pieces and back form a strong and enduring frame, while the pipes are so located as to be entirely enveloped in the heat of the fire-box, and being very thin the water therein is quickly and thoroughly heated, and in case of the stopping of the induction or eduction pipe by foreign matter or by ice these pipes, instead of bursting as the more substantial and thicker cast-iron water-backs do, will split, causing no greater damage and inconvenience than the mere destruction of the pipe and the putting out of the fire by the discharge of the water therefrom.
- 15 What I claim as new, and desire to secure by Letters Patent, is—
1. A water-back constructed and adapted to be inserted horizontally in the fire-box of a stove or range, consisting of two cast-iron end pieces—one at each end—each end piece having one or more water-chambers, in combination with a wrought-iron pipe or pipes con-

necting said end pieces, each connecting-pipe leading into a chamber of an end piece, and an induction and an eduction water-pipe, 25 substantially as described.

2. A water-back consisting of cast-iron head-pieces A and A', provided with chambers B and B', and a rear wall, G, in combination with a wrought-iron induction-pipe, C, wrought-iron intermediate pipes, D and E, and an eduction-pipe, F, substantially as described. 30

3. In a water-back, cast-iron heads A and A' and connecting wrought-iron pipes, in combination with a cast-iron wall, G, provided with draft-apertures H H, substantially as described. 35

In testimony whereof I affix my signature in presence of two witnesses.

JAMES H. SPENCE.
